UNITED STATES PATENT OFFICE

HERBERT J. MELVILLE AND HAROLD E. ATCHISON, OF CHICAGO, ILLINOIS, ASSIGNEES
TO THE CURTISS CANDY COMPANY, OF CHICAGO, ILLINOIS, A CORPORATION OF
ILLINOIS

CANDY-SLAB DIVIDER

Application filed March 31, 1927. Serial No. 179,839.

This invention relates to candy machines and more particularly to machines for dividing bars into segments, although it may be employed with equal advantage for other purposes.

5 It contemplates more especially the provision of means for dividing slabs of candy into bars of predetermined size without the subjection thereof to cutters or other undesirable expedients.

Known slab dividers resort to cutters and similar expedients which are not altogether satisfactory in that such devices require intermittent movement of the slabs to permit 10 actuation of the cutters at predetermined intervals of rest. This necessarily involves a complex structure which is not conducive to the best results.

Further, production is retarded considerably due to the necessity of providing intermittent motion in operating machines of such character. As a consequence thereof, it is highly desirable to provide a machine which is continuously operable to segregate 15 slabs into component segments of uniform size without effecting the continuity of operation or requiring numerous replacements of cutters and similar mechanism employed in lieu thereof.

One object of the present invention is to 20 simplify the construction and improve the operation of devices of the character mentioned.

Another object is the provision of means 25 for continuously effecting the division of successive slabs into uniform segments without interruption to the continuity of operation.

Still another object is the provision of 30 simple means for breaking slabs into segments, which do not require frequent replacements.

A further object is to provide means for 35 moving slabs along a predetermined path in conjunction with means for obstructing the path to effect a successive division of the slabs into segments.

A still further object is to provide means 40 for effecting an instantaneous change in directional movement of articles to effect the

segregation thereof into uniform segments.

Other objects and advantages will appear from the following description of an illustrated embodiment of the present invention.

55

In the drawings:

Figure 1 is a plan view of a machine embodying features of the present invention;

Figure 2 is a sectional view in elevation taken substantially along line II-II of 60 Figure 1;

Figure 3 is a sectional view taken substantially along line III-III of Figure 2;

Figure 4 is a sectional view taken substantially along line IV-IV of Figure 2; 65

Figure 5 is a fragmentary side view in elevation of the adjustable roller supporting means shown in Figure 2; and

Figure 6 is a perspective view of a slab capable of division with a machine of the 70 type disclosed herein.

The structure selected for illustration comprises a frame 10 consisting, in this instance, of a plurality of parallel spaced channel bars 11 superposed above similarly 75 disposed channel bars 12, they being fixed in any suitable manner to vertically disposed standards 13 which maintain the channel bars 11 and 12 in the desired relation.

A pair of rollers 14 and 15 are journalled 80 on the frame 12 in spaced parallel relation to carry a conveyor, in this instance an endless belt 16, therebetween. The conveyor 16 is movable in a clockwise direction so 85 that articles in the form of slabs may be placed thereon and carried along a predetermined path toward instrumentalities to effect the division thereof in a manner to be hereinafter described.

Candy slabs 17 are carried by the conveyor 16 along a predetermined path between guide bars 18 disposed slightly above the carrying face of the conveyor 16, the guides 18 depending from spaced bars 19 95 disposed transversely thereof and formed integral therewith to define, in this instance, two lanes of travel. The bars 19 are fixed to confronting uprights 20 secured in any suitable manner to the channel bars 11 (Fig. 100

ure 3) to suitably support the guides 18 in the desired position to define distinct lanes of travel for the slabs carried therebetween.

Another conveyor 21 is carried by a pair of rollers 22 and 23, the latter being disposed vertically above the roller 15 with the roller 22 positioned to the left thereof to define a horizontally disposed conveyor face 24. The face 24 confronts that portion of the conveyor 16 to the right of the terminal end of the guides 18 so that the slabs which are directed therebetween will impinge against the belt 21 to effect the entry of the slabs between the conveyors 16 and 21, the latter having the face 24 thereof co-acting with the conveyor 16 to embrace the surfaces of the slabs 17. It will thus be apparent that the slabs 17 are frictionally geared between the conveyors 21 and 16 which are possessed of the same linear velocity.

Means are provided to effect the division of the slabs which are preferably scored at uniform intervals as designated by numeral 25, to weaken the slab in the vicinity of the score so that stresses will be set up therein to effect the separation of the slabs 17 into segments responsive to an instantaneous change in directional movement thereof.

The dividing means, in this instance, comprises a roller 26 disposed in the path of the articles, in this instance the slabs 17, to obstruct the natural movement thereof, thereby necessitating substantially an instantaneous change in the direction of its movement. The slabs 17 impinge against the roller 26 which preferably turns in a clockwise direction to direct the slabs upward intermediate the rollers 23 and 26 which travel in opposite directions and actually embrace the confronting adjacent surfaces of the articles which are carried therebetween as a result of frictional contact with the co-operating rollers 23 and 26. It is to be noted that this change in direction produces a bending torque in the slabs 17 so as to effect a successive division thereof in the vicinity of the weakened portions defined by the scores 25.

To enable the segments to be discharged at any selective position, a conveyor 27 is carried by the roller 26 and another roller 28 spaced therefrom so as to carry the segments thereon to a suitable spout 29 disposed adjacent therewith to direct the discharge of the segments to a suitable container 30. The container 30 is supported in the desired position by means of a bracket 31 fixed to a standard 13 of the frame 10 by means of the fasteners 32 of standard construction.

It is desirable to provide means to accommodate slabs of different thicknesses to effect the division thereof in a manner described herein. Accordingly the rollers 15, 23, and 26 are preferably rendered adjust-

able so that the distances therebetween may be selectively varied by providing the extremities of the shafts 33 of the rollers 23 and 26 with suitable brackets 34 having vertical, internally threaded bores 35 (Figure 5). The bores 34 threadedly receive externally threaded studs 36 which are rotatably journaled between the superposed channel bars 11 and 12 on either side of the frame 10, they being journaled in suitable bearings 37 provided in the channel bars. The upper extremities 38 of the threaded studs 36 are of polygonal configuration so that a wrench or other suitable device may be suitably attached thereto to selectively 80 rotate the stud shafts 36 in an endeavor to raise or lower the rollers 23 or 26, or both, with respect to each other or the roller 15.

The tension of the conveyor belts 16, 21, and 27 should be properly tensioned about 85 their respective rollers, they being selectively adjustable for this purpose in that the rollers 14, 22, and 28 are movable in a horizontal or other suitable direction. The rollers 14, 22, and 28 are carried by shafts 39 rotatably mounted in journal boxes 40 which are movably mounted in horizontally disposed guides 41 which terminate in an upstanding lug 42. A threaded stud 43 of standard construction has the extremity 90 thereof rotatably mounted in each of the journal boxes 40 with the threaded shank thereof projecting through a suitable correspondingly threaded aperture in the upstanding lug 42. Movement is imparted to the journal boxes 40 by turning the studs 43 in the desired direction whereupon a nut 44 threaded on the shank of each of the studs 43 can be turned to a suitable position to co-operate with the upstanding lug 44 to maintain the journal boxes 40 in their desired position, thereby enabling individual tension control of the belts carried therearound.

Movement is imparted to the various conveyors by meshing a chain 45 with sprocket wheels 46 provided on each of the rollers 14, 22, and 28, which have idlers such as the sprockets 47 and 48 interposed therebetween in suitable positions to impart the desired directional movement to the conveyors 110 carried about the rollers 14, 22, and 28. The idler sprocket 48 is in this instance journaled in a suitable bracket 49 which is pivotally mounted at the free extremity thereof to a cross member 50 by means of a pin 51, the idler 48 being maintained in mesh with the chain 45 owing to a spring 52 interposed between the arm 49 and a standard 13 of the frame 10, this arrangement offering a suitable manner of maintaining the desired 115 tension in the driving chain 45 which is geared to a pulley 53 by virtue of the sprocket 54 fixed to a shaft 55 carrying the pulley 53.

Movement is imparted to the pulley 53 by 120

a belt 56 in frictional contact with the periphery thereof, the belt 56 being driven by any suitable power source such as an electric motor 57 having a pulley 58 fixed to the armature thereof to frictionally engage the driving belt 56. As shown, the electric motor 57 is suitably supported on the cross member 50 in an obvious manner to control the linear velocity of the various conveyors described hereinabove.

10 Various changes may be made in the embodiment of the invention herein specifically described without departing from or sacrificing any of the advantages thereof as defined in the appended claims.

15 We claim:

1. In combination, means for moving an article along a predetermined path and comprising paired carriers traveling in unison and other carrier means cooperating with said paired carriers for effecting a change in directional movement of said article whereby division of such article is effected.

2. The combination with an endless belt of a second belt disposed thereover, the two providing a path of slightly greater width than an article to travel therealong, and another belt disposed in proximity of the discharge end of said path to forcibly alter the direction of movement of articles travelling in said path, said forcible alteration in movement being effective to divide said article into segments.

3. The combination with means for conveying an article along a predetermined path and comprising parallel belts both of which engage said article, of another belt means obstructing said path and cooperating with one of said parallel belts to convey said article along another path whereby such article is divided into sections corresponding thereto.

4. The combination with an endless belt of a second belt disposed thereabove in parallelism therewith, the two belts providing a path for a slab-like article, another belt disposed in proximity of the discharge end of said first mentioned endless belts to forcibly alter the direction of sections of articles carried on said first referred to parallel belts, said forcible direction alteration being effective to divide said article into sections, and means for discharging said segments.

5. The combination with an endless belt of a second belt disposed in parallelism therewith, another belt disposed in proximity of the discharge end of said first mentioned endless belts to forcibly alter the path of articles carried between said first referred to belts, said forcible path alteration being effective to divide said article into sections, means for discharging said sections, and means disposed in the path of

said discharging means for receiving said sections.

6. The combination with a belt conveyor, of another belt disposed in confronting relation with said first named conveyor to provide a narrow passage for a slab like article, a conveyor disposed in a position to obstruct the path of an article carried intermediate said other belts and cooperating with one of said other belts to provide a second narrow passage at an angle to said first referred passage, and means for driving said belts in a direction to effect the reception of articles on said obstructing conveyor.

7. The combination with means for carrying slab-like articles thereon and along a predetermined path, driven means confronting a portion of said carrying means, the two means being adapted to embrace such articles, other means disposed in the path of said articles in spaced relation to the discharge end of said carrying and confronting means and providing article gripping means to effect a directional change in the movement of such articles for the purpose of breaking from such articles sections thereof.

8. In a device of the character described, a belt, another belt confronting said first named belt in spaced relation thereto to hold articles therebetween, another belt disposed in the path of an article held between the first two referred to belts to grip a portion of such article to change the directional movement thereof to effect a division of said article into sections, said last named belt being effective to discharge said segments at a predetermined position.
